No. 36,833.

Patented March 8, 1904.

UNITED STATES PATENT OFFICE.

ELLERSON L. BRAINARD, OF DANBURY, CONNECTICUT.

DESIGN FOR A JEWEL-CASKET OR SIMILAR ARTICLE.

SPECIFICATION forming part of Design No. 36,833, dated March 8, 1904.

Application filed December 21, 1903. Serial No. 186,135. Term of patent 3½ years.

To all whom it may concern:

Be it known that I, ELLERSON L. BRAINARD, a citizen of the United States, residing at Danbury, in the county of Litchfield and State of Connecticut, have invented a new, original, and ornamental Design for Jewel-Caskets or Similar Articles, of which the following is a specification, reference being had to the accompanying drawings, forming a part thereof.

Figure 1 is a front elevation showing my

design. Fig. 2 is an end elevation of the same.

I claim as new and desire to secure by Letters Patent—

The ornamental design for a jewel-casket or 15 similar article, as shown.

ELLERSON L. BRAINARD.
